Primary Examiner — Brandon M Rosati

Assistant Examiner — John A Voytek

(57) **CLAIM**

The ornamental design for a tire, as shown and described.

DESCRIPTION

FIG. 1 is a side perspective view of an embodiment of a tire showing our new design, it being understood that the tread pattern is repeated throughout the circumference of the tire tread, the opposite side being the same as that shown; FIG. 2 is a front elevational view thereof;

FIG. 3 is an enlarged fragmentary front elevational view of FIG. 2; and,

FIG. 4 is a side elevational view of the left side thereof, the opposite side being the same as that shown.

In the drawings, the solid line tire tread comprises the claim. The broken lines defining the sidewall, inner bead, shoulder portions, tread groove walls and the peripheral boundary between the claimed tire tread and the sidewall depict environmental subject matter that forms no part of the claimed design.
